UNITED STATES PATENT OFFICE

JESSE G. KING, OF DAYTON, OHIO, ASSIGNOR, BY MESNE ASSIGNMENTS, TO GENERAL MOTORS RESEARCH CORPORATION, OF DAYTON, OHIO, A CORPORATION OF DELAWARE

PUMP FOR REFRIGERATION SYSTEMS

Application filed August 3, 1920. Serial No. 400,894.

This invention relates to devices for transmitting power thru a sealed partition or wall, for example, to arrangements for driving refrigerating compressors entirely sealed within 5 a casing, by means of a prime mover disposed outside of the casing.

One of the objects of the invention is to provide an improved power transmitting device in which the driving and driven elements 10 are completely sealed from each other by a fluid-tight partition.

More specifically it is an object of the invention to provide an improved power transmitting device in which the elements are 15 sealed from each other by a flexible metal partition.

Another object of the invention is to so arrange such a partition that it will have great endurance or long life.

20 Another object is to so arrange the partition that it will be subjected to the minimum stress under operating conditions.

In refrigeration system of the compression type it is common practice to enclose the 25 pump or compressor in a housing and to drive the pump by a shaft passing thru a wall of the housing. In such cases it is necessary to use some means such as a packing gland or stuffing box around the shaft where it passes 30 thru the wall in order to prevent leakage of the refrigerant. Such packing devices cause considerable friction with consequent waste of power and moreover frequently become leaky from wear after a short period of use. 35 One of the specific objects of the invention is to provide a refrigerating compressor with improved means for sealing the pump from the driving mechanism which eliminates the disadvantages mentioned.

40 Further objects and advantages of the present invention will be apparent from the following description, reference being had to the accompanying drawings, wherein a preferred form of embodiment of the present invention is clearly shown.

In the drawings:

Fig. 1 is a plan view with parts in section of a refrigeration pump constructed in accordance with the present invention.

50 Fig. 2 is a horizontal section of another

form of pump also constructed in accordance with the invention.

Fig. 3 is an end view of the pumps shown in Figs. 1 and 2 with the cover plate removed.

Figs. 4, 5 and 6 show certain details of the 55 apparatus.

The present application relates to improvements in the pumps forming the subject matter claimed broadly in application Serial No. 397,519, filed July 19, 1920, by the present applicant. 60

In the previous application, specific description and claims were to a form of pump in which the actuation was produced by means of an oscillating lever. In the present application there is shown a pump consisting chiefly of elements similar to those shown in the previous application but in which rotary motion is transmitted from the motor or other driving means to rotate an 70 element within the housing containing the pump and from the rotating element motion is transmitted to the pump proper.

In the drawings, in which preferred forms of embodiments of the invention are shown, 75 the housing for the pump is composed of a rigid portion designated by the numeral 10 and a flexible member or portion designated as a whole by the numeral 20. In Fig. 1 this flexible portion 20 is indicated as extending 80 laterally from the rigid portion 10 and in Fig. 2 the flexible portion 20 is indicated as a reentrant portion connected with the outer end of and extending into a hollow cylindrical protuberance extending laterally 85 from one side of the rigid portion 10 of the pump housing. In both cases, however, the rigid portion together with the flexible portion provides a housing within which the various elements of the pump are contained and which, as will hereinafter appear, is a hermetically sealed from the external atmosphere; the interior of the flexible member being in communication with the interior of the rigid portion of the housing in the form of my invention shown in Figure 1, while in the form shown in Figure 2 the interior of the rigid portion is in direct communication with a space surrounding the exterior of said flexible member. 95 100

Within the rigid or main portion of the housing 10 are cylinders 12. In the construction shown in the drawings, these cylinders are illustrated as being formed by portions of the housing itself, but it will be readily understood that they may be separate from and entirely within the housing.

Adapted to be actuated within these cylinders 12 are pistons 13. In the form shown, there are two cylinders opposite and aligned, 10 with an intervening chamber between them, and two pistons adapted to operate in said cylinders, the pistons being carried upon a piston rod 14. This rod 14 is as shown in Fig. 3, preferably constructed in two portions, 15 each having one end shaped to form one half of the yoke 15, and bolted or otherwise secured together so as to form in effect a single rod with the yoke 15 in the middle portion. The piston rod 14 is provided at its central portion with the yoke 15 which coacts with the crank 16 upon the rotatable element 17 or 17' within the housing to produce the reciprocation of the rod and pistons. I prefer to rotate the element 17 by means of a driven member having power transmitting connection with the outside of the casing and partaking simultaneously of two kinds of motion. These two kinds may for example be 30 simple planar oscillation simultaneously in opposite directions as shown in my application No. 397,519, filed July 20, 1920, or as shown in Fig. 2 they may be rotation and nutation.

In the construction shown in Fig. 1 this 35 rotatable element 17 is the continuation of a shaft 18 which is enclosed by the flexible portion 20, of the housing. In the form shown in Fig. 2 rotatable element 17' is a separate element adapted to be rotated within the hollow protuberance aforesaid of the rigid portion 10 of the housing and provided with bearings 19 therein.

As shown in Figs. 1, 2 and 6, the shaft 18 is provided with a portion 18^a which rotates in a bearing 18^b in the housing, and is provided with a portion 18^c set at an angle to the rotating portion 18^b. It will be apparent that as the portion 18^a rotates, the portion 18^c nutates. The shaft is surrounded by a non-rotating sealing member generally denoted by 20 which includes a flexible tubular portion 21 and a rigid tubular portion 22. The flexible portion is preferably a corrugated metal bellows, one end of which is hermetically sealed to the casing and the other end of which is hermetically sealed to the rigid portion 22. The other end of the rigid tubular portion 22 is sealed to a cap 23 which 55 encloses the end of the shaft 18 forming a bearing for the latter, and is provided with an outer bearing 30. It will thus be apparent that the pump and its driving shaft 18 are entirely enclosed within a sealed housing.

60 The point 18^d at which the portions 18^a

and 18^c of the shaft 18 are joined, and consequently the point at which the change in the motion of the shaft takes place, is preferably situated on the normal axis of the bellows midway between the normal positions of the end planes of the bellows, the word "normal" 70 referring to the position of the bellows when free and at rest.

This tubular portion 22 of the flexible member 20 of the housing in turn extends 75 into a bearing 30 within a rotating driving member 31 which is attached to a second shaft 32 carrying pulley 33 to which driving power may be applied by means of a belt from a suitable source of power not shown. It is of course obvious that the shaft 32 may be otherwise driven, as by attaching it directly to an electric motor or other form of power producer. Or this shaft 32 may be eliminated and a motor attached directly to 80 driving member 31.

It is also obvious that the bearings throughout the device may be provided with anti-friction devices such as ball or roller bearings so as to increase the efficiency of the 90 apparatus.

In the form of structure shown in Fig. 2, instead of having the driving shaft for the pump entirely enclosed in the same housing with the pump, it is entirely outside of the 95 housing and is surrounded by the flexible portion of said housing.

In this form of pump, shaft 18 extends into the housing but is completely enclosed by the flexible reentrant portion 20 of the 100 housing composed of the same elements as are indicated in Fig. 1, and which form is an effective seal for the housing as a whole.

In this form of pump also the nutating portion of the shaft 18 extends into the cap 105 portion 40 at the inner end of the tubular portion 22 of the flexible housing, which cap portion in turn extends into a suitable bearing 41 in the rotatable element 17'.

In this form of pump as well as in the other 110 forms ball or roller bearings or other anti-friction devices may be used at whatever places may seem desirable.

In the form of pump shown in Fig. 2 the driving power is applied to the rotating portion 115 of the shaft which extends outside of the flexible portion 20 of the housing.

In Fig. 2 there has been indicated a form of piston which has been found to be satisfactory and give good results but which in its 120 specific form forms no part of the present application.

This form of piston consists of a body portion 50 having in its head a valve seat 51 and having within, a chamber 52 communicating with the valve 51. This piston is carried by the piston rod 14 which is provided with a longitudinal passageway 53 connected at its outer end with chamber 52 and at its inner end with the interior of the 125 130

housing. The piston rod is also provided with a valve surface 54 at its end adapted to coact with the valve seat 51 in the end of the piston.

5 The piston 13 is so mounted upon piston rod 14 as to permit a small longitudinal movement thereon. This is accomplished by means of the slots 55 in the piston rod coacting with the key members 56 in the pistons, which slots 10 are slightly wider than the key members.

To the outer ends of the cylinders 12 are attached the valve chambers 60 containing valves 61 providing for the outlet of the compressed fluid.

15 The flexible element 21 is illustrated more clearly in Figs. 4, 5 and 6 wherein it is shown in its ordinary position unattached to the other elements of the housing (Fig. 4) and wherein it is shown in the position assumed 20 when shaft 18 is inserted in the flexible part of the housing.

Fig. 5 illustrates the natural flexing of the bellows from which the location of point 18^d of the driving shaft is determined. In order 25 to increase the life of the bellows under repeated flexing, and to decrease the resistance offered by the bellows to such flexing and thus decrease the amount of power required to drive the apparatus, it is desirable to eliminate side stresses on the bellows and to subject the bellows to the minimum stress for a given displacement or amount of flexing. That is, when the bellows is flexed, all forces 30 transmitted from one corrugation to the next should act in lines which are as nearly as possible perpendicular to the planes of the corrugations and should not have any component in a direction parallel to such planes. And moreover such forces between any pair of 35 corrugations should be a minimum for a given flexure of the bellows. If such a bellows is supported with one end fixed and with its axis in a vertical line (so as to eliminate distortion produced by gravity) and the other end of the bellows is free, the bellows 40 will oscillate or vibrate freely when the free end has been subjected to a bending force applied at a single point and the force has been suddenly removed. During this 45 free vibration the bellows flexes in its natural manner and it will be evident that in such flexing the bending stresses set up in the bellows at any given point will be a minimum for a given amount of flexure. In flexing 50 naturally the bellows takes a form illustrated in Fig. 5 in which the normal axis $a-b$ always assumes the form of a simple curve $a-g-b'$ which I believe to be a circular arc normal to the end planes of the bellows and I believe that the free end $c-d$ of the bellows 55 always remains tangent to a sphere whose center is the point e located on the line $a-b$ midway between the normal positions of the end planes.

60 Accordingly I construct and arrange the

bellows and the driving member 31 and the driven member 18 (referring to Fig. 1) or the driving member 18 and the driven member 17' (referring to Fig. 2) so that during movement of the driving and driven members the bellows is constrained to flex in its natural manner, that is to say the plane of the free end of the bellows is maintained tangent to a sphere whose center is the point e . This is accomplished by locating the point of 70 change of motion of the member 18 at the point e . This may be effected by locating the bend 18^b in the shaft 18 at this point, or as shown in my application 397,519, referred to above, it may be effected by having the pivot of the oscillating member pass thru this point. 75

Thus in Fig. 5 the lines $a-e$ and $e-b'$ represent the axes perpendicular to the end planes of the bellows and these lines always 80 intersect at a point on the normal axis of the bellows midway between the normal positions of the end planes. The lines $a-e$ and $e-b'$ also represent the axes of the rotating and nutating portions of the shaft 18. Thus 85 during movement of the driving and driven members the bellows is flexed so as to oscillate between two positions on either side of its normal axis. In the case illustrated in Serial No. 397,519 this oscillation is simple 90 planar oscillation, while in the embodiment of the invention shown in Figs. 1 and 2 a portion of the bellows nutates, the point e being referred to as the center of oscillation (or more specifically in cases where the bellows 95 nutates, as the center of nutation). 100

Fig. 6 shows in elevation the flexible portion 20 of the housing attached to cover plate 70 of the protuberance aforesaid as this portion of the apparatus appears when removed 105 from the remainder of the assembly shown in Fig. 2. The flexible portion of the housing, as shown in Fig. 6, is substantially the same in both forms of pump illustrated.

It is thought that the operation of the 110 present apparatus will be entirely obvious from the description and drawings and no detailed discussion will be given other than to indicate the path of fluid through the compressor.

Taking for example the structure shown in Fig. 2 the fluid to be compressed will be drawn in at the inlet 80 when it will pass through the passage-way 53 in the piston rod into chamber 52, through valve 51 into the compression chamber of the cylinder, this operation taking place upon the suction stroke of the piston. Upon being compressed the gas will pass out through the valve chamber 60 and outlet 81. 115

The flexible metallic element 21 as illustrated in Figs. 1, 2, 4, 5 and 6 may be of any suitable form but a form that has been found satisfactory and one that has given excellent results is what is known in the trade as a 120 125 130

“sylphon”. These sylphons are corrugated metallic tubes permitting considerable and frequent compression along their longitudinal axis and also permitting considerable and frequent angular movement between their ends. These articles do not form a part of the present application as they are already the subject of numerous patents and quite well known in the trade. It should be added that the form of sylphon that has been found satisfactory for the present purpose is the laminated or multiply form, this giving the greatest flexibility with the greatest strength.

15 It will also be noted that while there has been described a two cylinder compressor, a greater number of cylinders, (for example, four) might be found advantageous in special cases and such modification is contemplated.

20 While the form of mechanism herein shown and described constitutes a preferred embodiment of one form of the present invention, it will be understood that other forms might be adopted and various changes and alterations made in the shape, size, and proportion of the elements therein without departing from the spirit and scope of the invention.

25 What is claimed as new is:

1. A power transmitting device comprising in combination a wall; and means for transmitting power through the wall including a power transmitting member having a nutating portion, and a metal bellows sealed to the wall and connected to said nutating portion, the center of nutation of said nutating portion being substantially midway between the normal positions of the end planes of the bellows.

30 2. A power transmitting device comprising in combination a wall; and means for transmitting power through the wall including a power transmitting member and a metal bellows sealed to the wall and connected to said member, said power transmitting means including means for nutating a part of the bellows about a center substantially midway between the normal positions of the end planes of the bellows.

35 3. A power transmitting device comprising in combination a wall; and means for transmitting power through the wall including a power transmitting member, and a metal bellows sealed to the wall and connected to said member, the power transmitting means including means for nutating a part of the bellows to cause the bellows to partake of its natural flexing movement.

40 4. A power transmitting device comprising in combination a wall; and means for transmitting power through the wall including a power transmitting member, and a metal bellows sealed to the wall and connected to said member, the power transmit-

ting means including means for nutating a part of the bellows so that the stresses set up in the bellows by the nutation are a minimum.

45 5. A power transmitting device comprising in combination a wall; and means for transmitting power through the wall including a power transmitting member partaking simultaneously of two movements, and a metal bellows sealed to the wall and connected to said member, and the point of change of motion in said member being located substantially midway between the normal positions of the end planes of the bellows.

50 In testimony whereof I hereto affix my signature.

JESSE G. KING.
